ALAN MACDONALD, OF SAN FRANCISCO, CALIFORNIA, ASSIGNOR TO SAN FRANCISCO SHIP BUILDING CO., OF SAN FRANCISCO, CALIFORNIA, A CORPORATION OF CALIFORNIA.

REINFORCED CONCRETE CONSTRUCTION ESPECIALLY ADAPTED FOR CONCRETE SHIPS.

1,264,314.

Specification of Letters Patent.

Patented Apr. 30, 1918.

Application filed November 1, 1917. Serial No. 199,621.

To all whom it may concern:

Be it known that I, ALAN MACDONALD, a citizen of the United States, residing at the city and county of San Francisco and State of California, have invented certain new and useful Improvements in Reinforced Concrete Construction Especially Adapted for Concrete Ships, of which the following is a specification.

10 My invention relates to reinforced concrete construction especially adapted for concrete-ships and it consists in the novel stirrup reinforcement, in connection with the main reinforcements of the walls and 15 beams of the ship, as I shall hereinafter fully describe, by reference to the accompanying drawings, in which—

Figure 1 is a sectional view, broken, of the side and bottom of a concrete ship showing 20 my improved stirrups in connection with the main reinforcement of the walls and beams.

Fig. 2 is a detail of the side of the ship showing the wooden-forms and the manner 25 of placing the stirrups.

Fig. 3 is a similar detail of the bottom of the ship.

Fig. 4 is a view of the two-part stirrup.

1 indicates the side and 2 the bottom of 30 the ship, both formed of concrete. 3 are the beams of the side and 4 are the beams of the bottom. The side beams are horizontally disposed, and the bottom beams vertically disposed, as shown.

35 5 are the steel bars constituting the main reinforcement of the side wall, and 6 are the steel bars of the main reinforcement of the bottom. 7 and 8 are the steel bars of the side beams and bottom beams respectively.

40 9 are my improved steel stirrups. They are made in two separate parts or members, as seen in Fig. 4. These are symmetrical and opposite, each member having extremities 10 at right angles to the body. At one 45 end these members hook over the main reinforcing bars 5 and 6 in the side and bottom respectively and at the other end, the extremities 10 of the stirrup overlap and they hook over the bars 7 and 8 of the side and bottom beams respectively. The advantage of these two part stirrups will be

understood in connection with their manner of placement, illustrated by Figs. 2 and 3. In Fig. 2, 11 indicates the wooden forms, which at the top of the side beam 3 are left open to pour the concrete. In Fig. 3, 12 shows the wooden forms, which likewise at the top of the bottom beam 4 are left open for the concrete. By splitting or halving the stirrups, I am enabled to carefully erect 55 the beam steel, side wall steel and bottom steel and then insert the split-stirrups at the sides.

It is customary in reinforced concrete construction of beams, to build forms, place the 60 steel stirrups of the ordinary form which is a single bar bent to rectangular shape, with the extremities separated but adjacent at one end and then lay the main reinforcement. This procedure is possible since 65 these beam structures extend below the slab and the concrete is poured in from the top.

In a concrete-ship, however, where the sides are vertical, the beams thereof being 70 horizontal, and where the beams of the bottom are vertical and extend upwardly from said bottom, it is very difficult to install the common form of one-piece stirrup. Owing 75 to the thinness of the walls and beams in concrete-ships, due to the necessity of keeping the weight down, it is imperative that the stirrups shall pass around and engage the steel bars of the sides and of the bottom, and the bars of the beams. In order 80 to use the common form of stirrup in this connection, it would be necessary to first set the stirrup in engagement with the wall and bottom steel, after which the horizontal beam steel could be threaded in from the ends. To do this would not only be expensive, 85 but very difficult, and probably would result in poor workmanship. But with my stirrup, the members can be readily inserted, as I have herein described, thereby saving expense and making it possible to do a cheap 90 and accurate job.

I claim:—

In concrete construction and in combination with its vertical and horizontal walls, and the beams thereof extending therefrom 100 horizontally and upwardly respectively, and the main reinforcing bars of said walls and

beams, the two part stirrups comprising opposing members with bent extremities those at one end of the stirrup engaging the reinforcing bars of the walls and those at the other end overlapping and engaging the reinforcing bars of the beams.

In testimony whereof I have signed my

name to this specification in the presence of two subscribing witnesses.

ALAN MACDONALD.
